H. H. LAMPERT

ADJUSTABLE SHORE

Filed July 1, 1924

Witness:
W. X. Olson

Inventor:
Henry H. Lampert
Rummel and Rummel

UNITED STATES PATENT OFFICE.

HENRY H. LAMPERT, OF CHICAGO, ILLINOIS.

ADJUSTABLE SHORE.

Application filed July 1, 1924. Serial No. 723,544.

The main object of this invention is to provide an improved adjustable shore of light construction, with maximum strength; to provide a shore with a self-bracing head, 5 carrying a head timber to which forms can conveniently be nailed; to provide an adjustable shore in which shore timbers can be used without nailing or cutting and hence be available for repeated use; to provide 10 a shore with a base supporting shelf, which will in action automatically clamp the timber base and act as a brace to the section holding the shelf; to provide a head section and a foot section of economical construction 15 for quantity production so that they are interchangeable in construction work.

An illustrative embodiment of this invention is shown in the accompanying drawing, in which—

20 Figure 1 is a complete shore supporting a temporary form.

Figure 2 is a section at line 2 using four angle irons.

25 Figure 3 is a section at line 2 using two channel irons.

Figure 4 is a section at line 2 using two angle irons.

Figure 1 is a complete improved shore, comprising a shore timber 1, seated upon a 30 shelf 2, which is supported in angular spaced notches 3 cut in the supporting angle irons 4, which form a part of the rectangular frame of the foot or jack section. The angle irons 4 are secured to a casting 5, 35 which has a threaded aperture 6 to receive a screw 7, which has swivel connection with a foot plate 8. The upper end of the jack section is a rectangular frame, which is held spaced by a riveted collar 9. Coacting with

40 the upper end of the shore timber is a head section comprising a rectangle of similar angle irons 4, to which are secured right-angle angle bars 10, having ends supported by braces 11. The braces 11 project above 45 the angle iron 10 and are provided with nail holes 12 for the purpose of securing a head timber 13. In Figure 1, an illustrative sketch of a temporary form is shown resting upon and nailed to the head timber. 50 This temporary form comprises strips 14 which are nailed to the head timber, with upright supports 15 and braces 16.

One of the improved features of this invention is the form and action of the shelf

2. The shelf provides a quick setting of 55 the shore timber by slipping it in place and following it up with the shelf 2. This makes it possible to use standard length shores from stock without cutting. The direct load upon the shore is carried by the 60 self 2. The base of the shelf has angular bearing surfaces which coact with the angular notches 3, with clearance between the edges of the shelf and the bottom of the notch, so that when the load is applied 65 through a stress on the shore timber the shelf bearings are forced into the notches, drawing the corner angle irons 4 in closer contact with the timber. At the same time the action tends to stiffen the rectangular 70 frame of the jack at its weakest point, and at the place of greatest stress.

A cross section of the jack section 1, at the position of the shelf, is shown in Figure 2, in which the shelf coacts with the four angle irons, drawing them together. An equivalent arrangement is shown in Figure 3, in which the shelf rests upon angular notches cut in two channel irons. This construction gives an increased pinching action, but this increase is obtained by a sacrifice in the light construction. An equivalent result is shown in Fig. 4, in which the shelf 2 rests in a frame made of two angle irons which are drawn up to the shore timber and braced by the action of the shelf 2. 80

85 Although but one specific embodiment of this invention has been herein shown and described, it will be understood that numerous details of the construction shown may 90 be altered or omitted without departing from the spirit of this invention as defined by the following claim.

I claim:

In combination in an adjustable shore 95 opposed strut members having inwardly extending flanges and downwardly sloping notches in said flanges, a second strut member slidable between said strut members, and a shelf having angularly inclined edges 100 adapted to be engaged in opposite notches in said flanges to support the slidable member and thereby draw the opposed strut members inwardly to grip said slidable member. 105

Signed at Chicago, this 28th day of April, 1924.

HENRY H. LAMPERT.
